UNITED STATES PATENT OFFICE

2,607,337

OIL HEATER

William J. Miller, Youngstown, Ohio

Application June 22, 1950, Serial No. 169,693

1 Claim. (Cl. 126—343.5)

1

This invention relates to heating apparatus and more particularly to apparatus for efficiently and rapidly heating a fluid heat exchange medium such as a suitable oil.

The principal object of the invention is the provision of an oil heater.

A further object of the invention is the provision of an oil heater incorporating novel design and construction enabling extremely rapid and efficient transfer of heat from combustion to a fluid heating medium.

A still further object of the invention is the provision of an oil heater including a novel fluid jacketed combustion chamber.

A still further object of the invention is the provision of an oil heater of design and construction contributing to the economical formation of the heater and the compact size thereof.

The oil heater shown and described herein is particularly adapted for use in heating bituminous material such as asphalt and the like and wherein hot oil from the heater, as disclosed herein, is circulated through tanks, tank cars or other containers of asphalt in suitable heat exchange coils therein for the purpose of liquefying the asphalt to the point where it can be pumped from the said containers.

The efficiency of operation of the oil heater herein makes possible the extremely rapid heating and liquefying of asphalt in storage tanks and the like which contributes to the economic handling of such products as it eliminates time heretofore wasted in attempting to heat asphalt in such containers by steam generators as heretofore known in the art.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a cross sectional side elevation.

Figure 2 is a vertical section on line 2—2 of Figure 1.

Figure 3 is an end view taken on line 3—3 of Figure 1.

By referring to the drawings and Figures 1 and 2 in particular it will be seen that the hot oil heater comprises a semi-cylindrical tank 10

5 having end walls 12 and 13, respectively, and supported on a suitable base 14. The semi-cylindrical tank 10 has a secondary semi-cylindrical tank 15 of smaller size positioned within the semi-cylindrical tank 10 and defining a chamber 16 surrounding the sides and one end of the secondary tank 15 so that it is in effect jacketed by the tank 10. The chamber 16 is normally substantially filled with a fluid heat exchanging medium such as suitable heat exchange oil so as to enclose the tank 15.

10 The tank 15 has an end wall 17 therein spaced with respect to the end wall 12 of the tank 10 and the other end of the tank 15 is secured to the end wall 13 of the tank 10. The tank 15 has a longitudinally extending, transversely arcuate baffle 18 located in the uppermost portion thereof and which baffle extends from the end wall 13 to a point adjacent but spaced with respect 20 to the end wall 17.

An opening 19 formed in the end wall 13 communicates with the interior of the semi-cylindrical tank 15 in the end thereof opposite from the end wall 17 and into this opening fits 25 the nozzle or hood 19 of a burner 20 so that combustible fuel may be introduced into the tank 15 through the nozzle 19 and burned therein. A heat exchange coil 21, including a plurality of convolutions, the diameters of which are of a size 30 slightly smaller than the interior of the tank 15, is located in the interior of the tank 15, as best shown in Figures 1 and 2 of the drawings and the ends of the coil 21 extend outwardly through the end wall 13, one of the ends being indicated by the numeral 22 and the other by the numeral 23. The end 23 of the heat exchange coil 21 35 communicates with the outlet of pump 24 while the inlet of the pump 24 is in communication by way of an inlet pipe 25 with the chamber 16 in the tank 10. The end 22 of the coil 21 communicates with the chamber 16 in the tank 10 at a point near the uppermost portion thereof so that heat exchange oil in the chamber 16 will 40 also fill the heat exchange coil 21.

45 It will be observed that when the burner 20 is operated as by a motor 26 and the products of combustion introduced into the tank 15, they will flow longitudinally thereof about the heat exchange coil 21, upwardly around the far end 50 of the baffle 18 and longitudinally of the baffle 18 and immediately thereabove to a stack 27. It will be observed that the heat exchange action thus obtained is very efficient as the operation of the motor 26, in addition to operating the burner 20, also operates the pump 24 and con-

55

tinually circulates the liquid contents of the chamber 16 through the heat exchange coil 21. Additionally, the products of combustion are contained within the tank 15 which is jacketed by the tank 10 so that considerable heat transfer is obtained through the walls of the tank 15 directly into the liquid contents of the chamber 16 thereabout.

It has been determined that operating temperatures of approximately 600° F. are easily achieved and maintained in the hot oil heater disclosed herein with minimum fuel consumption and that the efficiency of the apparatus is much greater than any heat exchanger heretofore known in the art and particularly as used in connection with a liquid heating medium such as oil for subsequent circulation through asphalt containers and the like.

Still referring to Figure 1 of the drawings it will be seen that means for circulating hot oil through the chamber 16 to a container to be heated (not shown) is provided. Means comprising a valve-controlled pipe 28 from which hot oil may be pumped from the chamber 16 and a secondary valve-controlled pipe 29 through which hot oil may be returned to the chamber 16. It will be observed that the pipe 28 communicates with the upper part of the chamber 16 and adjacent the inlet communicating with the end 22 of the heat exchanger coil 21 so that the pump outlet communicates with the area of the chamber 16 containing the hottest oil. The fluid heating medium in the chamber 16 and the heat exchanger coil 21 is at atmospheric pressure as an upwardly projecting atmospheric vent 30 is provided in the tank 10.

It will thus be seen that the several objects of the invention are met by the hot oil heater disclosed herein.

Having thus described my invention, what I claim is:

A liquid heater comprising a horizontally disposed main container having front and rear end walls and upper and lower wall portions and side wall portions, an atmospheric vent extending from the main container, a secondary container disposed horizontally in the main container and having upper and lower wall portions and side wall portions and a rear end wall spaced inwardly from the corresponding walls of the main

container and thus providing a liquid-receiving space in the main container about the secondary container, the secondary container defining a combustion chamber, the front end of the secondary container being mounted against the front wall of the main container and closed by a portion of the said front wall of the main container, a transversely arcuate baffle plate extending horizontally in the combustion chamber and being secured across its front end to the said front wall and along its side edges to side wall portions of the secondary container, the rear end of said baffle plate being spaced inwardly from the rear wall of the secondary container, a source of products of combustion communicating with the secondary container through an opening in the front wall below said baffle plate, there being an outlet opening for products of combustion in the said front wall above said baffle plate, a circulating pump outwardly of the front wall, a coil in the combustion chamber substantially coextensive with the length of the baffle plate and having its convolutions adjacent the baffle plate and walls of the secondary container, said coil having end portions passing through the front wall below the baffle plate, one end of said coil being connected with said pump and the other end thereof being mounted through the front wall above the secondary container and communicating with the upper portion of the space within the main container, and a pipe having one end connected with the pump and its other end mounted through the front wall and communicating with the portion of the space in the main container under the secondary container.

WILLIAM J. MILLER.
